UNITED STATES PATENT OFFICE.

GEORGE E. KIMBALL, OF CHICAGO, ILLINOIS, ASSIGNOR, BY MESNE ASSIGNMENTS, TO FIRST TRUST AND SAVINGS BANK, TRUSTEE, OF CHICAGO, ILLINOIS.

AUTOMATIC TELEPHONE-EXCHANGE APPARATUS.

1,178,471.

Specification of Letters Patent.

Patented Apr. 4, 1916.

Application filed November 24, 1906. Serial No. 344,813.

To all whom it may concern:

Be it known that I, GEORGE E. KIMBALL, a citizen of the United States of America, and resident of Chicago, Cook county, Illinois, 5 have invented a certain new and useful Improvement in Automatic Telephone- Exchange Apparatus, of which the following is a specification.

My invention relates to interrupters, and 10 more particularly to interrupters for producing the automatic step-by-step operation of a selector—that is to say, the step-by-step operation by which a telephone selector switch finds an idle trunk line for a calling subscriber.

An object of my invention is to provide an improved and highly efficient interrupter.

Another object is to provide certain features of improvement and details of construction and combinations tending to increase the general efficiency of an automatic or semi-automatic telephone exchange system.

To the foregoing and other useful ends, 25 my invention consists in matters hereinafter described and claimed.

In the accompanying drawings, Figure 1 illustrates diagrammatically a group of switches and an interrupter for operating 30 said group. Fig. 2 is a perspective diagrammatic illustration of a trunk selector switch similar to the one disclosed in United States Letters Patent No. 815,321, granted March 13, 1906, to Keith, Erickson and Erickson.

35 The battery B may have its positive terminal grounded. The magnet H, say of sixty ohms resistance, is shown connected to my interrupter device A, by way of the conductor 32 and switch wiper i^4 , to the conductor 2. Now when the switch i^4 is closed onto the contact point 30 an energizing circuit is closed through the relay 3. Said circuit extends from ground G' through the winding of the relay 3, conductor 2, contact point 30, 40 switch i^4 , conductor 32, through the winding of the magnet H to the battery lead 4, thence through battery B and to ground G. Though the magnet H is in series with the relay 3 the former does not operatively energize, since the winding of the relay 3 is of high resistance, and consequently the current-flow is not sufficient to operate the comparatively low-wound coil H. The relay 3

upon energization attracts its armature 5, which operates to place the springs 6 and 7 in engagement. The engagement of said springs closes an energizing circuit through the relay 8 extending from ground G' through the springs 6 and 7, through the winding of the relay 8 to the battery lead 4, thence through battery B and to ground G. The relay 8 upon energization attracts its armature 9, which operates to place the springs 10 and 11 in engagement, whereby the relay 3 becomes short-circuited and a new energizing circuit is established through the magnet H for operating the latter. This energizing circuit extends from ground G' through the springs 10 and 11, conductor 12 and conductor 2, contact point 30, switch i^4 , 70 conductor 32, winding of the magnet H to battery lead 4, thence through battery B and to ground G. The short-circuit of the relay 3 extends from ground G' through the winding of the said relay, conductor 12, springs 75 11 and 10 to the ground G'. Accordingly the relay 3 deenergizes and the springs 6 and 7 disengage, thereby breaking the energizing circuit through the relay 8. The relay 8 in turn deenergizes and the springs 10 and 11 disengage, thus breaking the energizing circuit through the magnet H and removing the short-circuit of the relay 3. As soon as the short-circuit is removed from the relay 3 an energizing circuit is established, as before explained, and again the relay 3 operates to close the energizing circuit through the relay 8, which in turn closes the springs 10 and 11 in contact, thereby again establishing the energizing circuit through the magnet H, short-circuiting the relay 3. The magnet H is thus intermittently energized for any purpose, while the switch i^4 engages the contact point 30. The frequency of the energization of the magnet H may be varied 85 within certain limits by varying the tension of the spring 6. For instance, when the spring 6 is weak the operation is slower than when the said spring is stiff. Furthermore, the condenser 13 is provided to reduce the 90 sparking when the springs 10 and 11 disengage. My interrupter may be employed to interrupt any circuits for signaling, lamp flashing, sign flashing, etc. Suppose, for example, that it is desired to intermittently 95 100 energize the rotary magnet H of the selector 105

switch disclosed in said selector patent. My interrupter may be used, therefore, in connection with the said selector by removing the old interrupter springs thereof, and by 5 connecting the rotary magnet shown in said patent directly to the wiper i^4 , connecting the conductor 2 to the contact point 30 of the said patent. The side switch wiper of the said patent would correspond to or be 10 the same as the side switch wiper i^4 , and the contact points allotted to said wiper will correspond to the contact points allotted to the herein described wiper i^4 . The magnet H would, of course, be the rotary magnet of the 15 patent. The interrupted operations of the rotary magnet in the patent would then take place in the manner described in connection with the magnet H. The armature h of the magnet H will, of course, correspond to the 20 rotary armature of the rotary magnet of the said patent.

The relays shown in the accompanying drawings may be wound to any suitable resistance, but with a battery B of fifty volts 25 good results are obtained when the relay 3 is wound to a resistance of thirteen hundred ohms, and the relay 8 wound to a resistance of five hundred ohms.

The private magnet switch i^4 of the selector is, of course, automatically opened as 30 soon as an idle trunk line or trunk is found by the wipers of the selector. In this way the operation of the relays is continued, by the energizing of the private magnet of the 35 selector, until said private magnet is de-energized when the wipers of the selector move onto idle or non-busy contacts.

My improved interrupter can be used individually, one to each selector or other 40 switch, when used in an automatic or semi-automatic telephone system; but as indicated in Fig. 1, my interrupter may be used in connection with a group of switches. The rotary magnet H' of a second-selector switch 45 corresponds to the rotary magnet H, and the side switch wiper I^4 of the switch to which the rotary magnet H' belongs corresponds to the side switch wiper i^4 . Said side switch wiper I^4 is, of course, also controlled by a 50 private magnet, in the same manner as pointed out in connection with the side switch wiper i^4 of the other selector; and when the side switch passes to third position the interrupter circuit for the particular 55 rotary magnet H' is broken. Of course, the energizing circuit for the rotary magnet H' would be the same as the one for the rotary magnet H, with the exception that it includes the contact point 30', the side switch 60 wiper I^4 , and the rotary magnet H'. In other words, a group of trunk selectors or other switches may be operated by one interrupter, which latter is, of course, normally at rest. One of these selectors, as already 65 stated, is shown in Fig. 2. The line relays

14 and 15 are the relays through the medium of which the switch is operated by a telephone subscriber and are normally connected to the vertical and rotary line conductors 16 and 17, respectively. The subscriber, by 70 sending suitable impulses, operates the vertical line relay 14, which in turn operates the vertical magnet 18. This vertical magnet, through the medium of the usual mechanism, raises the shaft 19 for the purpose 75 of carrying the switch shaft wipers 20, 21 and 22 opposite some particular group of trunk-lines, which trunk-lines terminate in the terminals of the banks 23. After the wipers have been thus raised the rotary line 80 relay 15 is operated to energize the usual private magnet 24 which, by attracting and releasing its armature, permits the side switch C to trip to second position, whereby 85 the side switch wiper i^4 (Fig. 1) is carried into engagement with the contact point 30. This contact is connected with the interrupter relays by the conductor 2 through which the proper impulses are transmitted to the rotary magnet H and thence to the 90 battery lead 4, and through battery B to ground G. It is evident that after the circuit is closed for the rotary magnet H this magnet H is given impulses as long as the side switch wiper i^4 is in engagement with 95 the contact point 30, whereby, through the usual mechanism, the shaft 19 may be rotated and the shaft wipers advanced into engagement with any particular set of trunk terminals and, therefore, with the corresponding trunk-line. If the shaft has been raised to the second level, for example, it will be understood that if the first trunk is 100 idle the rotary magnet H will receive only one impulse, because the armature 25 of the rotary magnet will operate the armature 26 of the private magnet, which on returning to normal will cause the side switch to be tripped to third position. However, if the first trunk is busy the private wiper 22 105 will be carried into engagement with a grounded contact (the first private bank contact of the second row), whereby an energizing circuit is established through the private magnet 24. This private magnet 110 will then attract its armature 26 before the rotary armature 25 has time to fall back, and will hold this armature 26 down even after the rotary armature 25 has operated for the first step, thereby retaining the side 115 switch in second position until the rotary magnet H receives another impulse from the conductor 2. (See Fig. 1). Of course, the shaft 19 will then be rotated a second step, and if the next trunk is idle the energizing 120 circuit through the private magnet 24 will be broken, which private magnet will then abandon the armature of the private magnet to the rotary armature 25, which rotary armature will operate as in the first instance 125 130

to allow the private magnet armature to trip the side switch to third position. It will be understood, however, that the private magnet 24 will be retained energized 5 as long as the private wiper 22 is carried into engagement with the grounded contact. The selector switch is provided with the usual release magnet 27 which may be energized in the usual manner for restoring 10 the switch after a connection has been made with the trunk-line. This is usually done through the medium of the back-release relay 28 which is adapted to be energized over the seized trunk and through the private wiper 22. The said back-release relay 28 it will be seen directly controls the energizing circuit through the release magnet 27, so that when said back-release relay energizes, the release magnet 27 is energized 20 as a result, which release magnet then operates to attract its armature. The release magnet, upon thus energizing, latches the release mechanism, as is ordinarily the case, preparatory to restoring the same when the 25 release magnet is deenergized.

What I claim as my invention is:—

1. An interrupter comprising a plurality of mutually or reciprocally controlled relays, and step-by-step switching means having a magnet included in the energizing circuit of one of said relays and responsive to the interrupted current thus produced. 30
2. The combination of a first relay, a second relay, means by which the energizing 35 of the first relay energizes the second relay, means by which the energizing of the second relay deenergizes the first relay, a magnet intermittently energized by the successive energizing and deenergizing of said relays, 40 said magnet included in the energizing circuit of the first relay, and step-by-step switching means operated by the said magnet.

3. The combination of a first relay, a second relay, means by which the energizing 45 of the first relay energizes the second relay, means by which the energizing of the second relay short-circuits or shunts the first relay, a magnet intermittently energized by the successive energizing and deenergizing of said relays, 50 said magnet included in the energizing circuit of the first relay, and step-by-step switching means operated by the said magnet.

55 4. The combination of a first relay, a second relay, an energizing circuit for said first relay, means for closing said circuit, means by which the energizing of the first relay energizes the second relay, a normally 60 open connection by which the energizing of the second relay short-circuits or shunts the first relay, a magnet intermittently energized by the successive energizing and deenergizing of said relays, 65 said magnet included in the energizing circuit of the first relay, and

step-by-step switching means operated by the said magnet.

5. The combination of a first relay, a second relay, means by which the energizing of the first relay energizes the second relay, 70 means by which the energizing of the second relay deenergizes the first relay, a magnet intermittently energized by the successive energizing and deenergizing of said relays, a plurality of trunks, a trunk-selecting switch mechanism operated by said magnet, said magnet included in the energizing circuit of the first relay, and automatic means for stopping the operation of said relays 75 when an idle trunk is found.

6. The combination of a first relay, a second relay, means by which the energizing of the first relay energizes the second relay, means by which the energizing of the second relay short-circuits or shunts the first relay, 80 a magnet intermittently energized by the successive energizing and deenergizing of said relays, a plurality of trunks, a trunk-selecting switch mechanism operated by said magnet, said magnet included in the energizing circuit of the first relay, and automatic means for stopping the operation of 85 said relays when an idle trunk is found.

7. The combination of a first relay, a second relay, an energizing circuit for said 90 first relay, means for closing said circuit, means by which the energizing of the first relay energizes the second relay, a normally open connection by which the energizing of the second relay short-circuits or shunts the first relay, a magnet intermittently energized by the successive energizing and deenergizing of said relays, a plurality of trunks, a trunk-selecting switch mechanism 95 operated by said magnet, said magnet included in the energizing circuit of the first relay, and automatic means for stopping the operation of said relays when an idle trunk 100 is found.

8. In a telephone system, a plurality of 110 automatic switches, each switch provided with an operating magnet, and an interrupter common to said switches, said interrupter having a relay adapted to be energized in series with any one of said magnets, 115 the resistance of said relay being sufficient to prevent energizing of said magnets, and means controlled by said relay for short-circuiting the latter, whereby the magnets are energized.

9. In a telephone system, an automatic switch provided with an operating magnet, and an interrupter controlling the operation thereof, said interrupter provided with a relay adapted to be energized in series with 120 said magnet, said relay being of sufficiently high resistance to prevent energizing of said magnet, and means controlled by said relay for short-circuiting the winding thereof, whereby the magnet is energized. 125

10. In a telephone system, an automatic switch provided with an operating magnet, and an interrupter for controlling the operation of said switch, said interrupter provided with one relay adapted to be energized in series with said magnet, said relay being of sufficient resistance to prevent energizing of said magnet, a second relay controlled by said first-mentioned relay, and means con-

trolled by said second relay for short-circuiting the first relay, whereby the latter is deenergized and the said magnet energized.

Signed by me at Barberton, Summit county, Ohio, this 15th day of Nov., 1906.

GEORGE E. KIMBALL.
